BALL POINT PEN

Robert J. Harper, Scarsdale, Robert H. Ensign, Bronxville, and Sidney H. Bradd, Jr., New York, N. Y., assignors to Scripto, Inc., a corporation of Georgia

Application June 28, 1956, Serial No. 42,076

Term of patent 14 years

(Cl. D74—17)

Fig. 1 is a side elevational view of a ball point pen, showing our new design;

Fig. 2 is a front elevational view thereof;

Fig. 3 is a top plan view;

Fig. 4 is a sectional view taken on line 4—4 of Fig. 1, the interior thereof being indicated indeterminately for adaptation to a particular ball point mechanism; and

Fig. 5 is a bottom plan view of the ball point pen shown in Fig. 1.

We claim:

The ornamental design for a ball point pen, as shown and described.
